Patented Feb. 1, 1921.

FIG. 1

FIG. 2

FIG. 3

FIG. 4

William J. Newton Inventor,

By his Attorney,
Emery, Bratt, James, Vane

UNITED STATES PATENT OFFICE.

WILLIAM J. NEWTON, OF LYNBROOK, NEW YORK, ASSIGNOR, BY MESNE ASSIGNMENTS, TO JOHN G. LIVINGSTON, OF WOODMERE, LONG ISLAND, NEW YORK.

ELECTRIC WALL-SWITCH.

1,366,924.

Specification of Letters Patent. Patented Feb. 1, 1921.

Application filed December 5, 1916. Serial No. 135,136.

To all whom it may concern:

Be it known that I, WILLIAM J. NEWTON, a citizen of the United States, and a resident of the village of Lynbrook, county of Nassau, and State of New York, have invented an Improvement in Electric Wall-Switches, of which the following is a specification.

My invention relates to electric wall switches, such as are used to control the circuits of electric lighting fixtures in buildings, and more particularly to switches of the toggle or lever type.

I aim to provide a switch of the toggle or lever type, which will be positive in its operation and will break the contact with great rapidity, while at the same time it is of the greatest simplicity, contains the fewest possible number of parts and is, therefore, inexpensive to manufacture. As an example of the simplicity of my improved switch, I will cite the fact that it contains only four moving parts, and that two of said parts are oscillating parts, pivoted upon a common support.

In the drawings, Figure 1 is a plan view of my improved switch. Fig. 2 is a sectional view thereof, taken on the line 2—2. Fig. 3 is a sectional view taken on the line 3—3, and Fig. 4 is a view of a cover, adapted for use with my improved mechanism.

My improved switch comprises a base 1 of insulating material, which may be porcelain, molded insulation or other suitable material, upon which is mounted a bridge plate 2, screwed to the base by means of screws 3—3, and apertured at 24. Bridge 2 is bent upwardly in the form of an inverted U, the opposite legs of which are traversed by a pin 4, which carries the manual operating handle 5, pivotally mounted thereon. The opposite legs 22 of the U shaped bridge 2 are also pierced to provide a bearing 21 for the ends of a U shaped blade carrier 6.

Blade carrier 6 is provided with an upwardly extending projection 7 (see Fig. 2), upon which is mounted a horizontally disposed U shaped switch blade 8, which is supported from the blade carrier by suitable insulation 9.

The blade member 8 is preferably made of some spring metal, such as brass, so that the ends thereof tend to be sprung away from one another, in order to produce a positive contact with contact plates 10—10.

Contact plates 10—10 are mounted upon

insulating base 1, by means of screws 11—11, which may be used as binding posts or terminal screws for the supply wires. Contact plates 10 are bent downwardly into an aperture 12, formed in the base plate 1, so as to be securely supported by the base plate in their proper positions, and to make contact with the U shaped switch blade 8. Holes 13—13 are provided in the insulating base for the supply wires.

Extending between the blade carrier 6 and the operating handle 5, is a switch operating rod 14. Said rod 14 is attached to the operating handle 5, by a pin and slot connection at 15, and passes through an aperture in the U shaped switch blade carrier 6. A spring 16 surrounds the switch operating rod 14 and is held in compression between the blade carrier 6 and shoulders or other suitable stop 17 formed or mounted upon operating rod 14.

In order to eliminate the necessity for stops for the operating mechanism, and thereby to simplify the apparatus, aperture 12 of the base 1 is so formed that the switch carrier 6, when the switch is moved to the open position, brings up against the wall of aperture 12, as shown in the dotted lines of Fig. 2. In order to arrest the movement of the blade carrier in the closed position, a stop or shoulder 18 is formed upon one or both of the upstanding legs of the bridge 2.

Fig. 4 shows the simple type of cover which may be used with my improved switch. It consists of a spun shell, which fits tightly over the shoulder 19 of the base 1, and is provided with an aperture, through which the operating handle passes. By reason of the compact arrangement of my improved switch mechanism, it is possible to use a circular cover of this type, which may be sprung over the insulating base and requires no further means of attachment.

The operation of my improved mechanism is as follows: Assuming the parts to be in position, shown in full lines in Fig. 2, the switch is then in the closed position, the opposite legs of the U-shaped blade 4 being in close contact with the depending arms of contacts 10. Movement of the operating handle 5 toward the position shown in dotted lines in Fig. 2, produces a movement of operating rod 14, toward the right and downwardly through the aperture formed in the lowermost part of blade carrier 10.

6. This produces a compression of spring 16 until the pivot 15 has passed through a line drawn between pivot 4 and the aperture in the lowermost portion of blade carrier 6.
- 5 Up to this point the effect of the increased compression of the spring has been to hold the blade carrier 6 in the closed position, but as soon as this position is passed, the effort of the spring is exerted in the opposite
- 10 direction and the switch opens quickly, its movement being arrested by the wall of aperture 12, in the base 1.

15 While I have only shown one example of my improved switch, I do not wish to be confined thereto, as it will be evident to those skilled in the art, that many modifications may be made, without departing from the spirit of my invention.

I claim—

- 20 1. An electric switch, comprising a

U shaped bridge, having an aperture and two spaced legs, an oscillating operating handle passing through the aperture, and pivoted upon said spaced legs, a U shaped carrier also pivoted between said legs, and 25 having an aperture at its lowermost part and an operating rod passing through said aperture in the carrier, and connected to said handle.

2. An electric switch, comprising a base, 30 an apertured U shaped bridge, an operating handle pivoted on the legs of the bridge and passing through the aperture, a spring, and a carrier operable by said spring and containing the same and also pivoted upon said 35 bridge.

In testimony whereof, I have signed my name to this specification this 4th day of December, 1916.

WILLIAM J. NEWTON.
